UNITED STATES PATENT OFFICE.

EARL D. CHURCH, OF HARTFORD, CONNECTICUT.

RIFLE-RANGE SHOT-INDICATOR.

1,139,846.

Specification of Letters Patent.

Patented May 18, 1915.

Application filed April 15, 1910. Serial No. 555,697.

To all whom it may concern:

Be it known that I, EARL D. CHURCH, a citizen of the United States, residing at Hartford, in the county of Hartford and State of Connecticut, have invented a new and useful Improvement in Rifle-Range Shot-Indicators, of which the following is a specification.

This invention relates to an apparatus 10 which is designed to be used in connection with rifle ranges, either indoor or field ranges, for the purpose of indicating to the marksman and the scorer at the firing line, the value and position of each shot as fired.

15 The object of this invention is to provide a simple and cheap apparatus which can be conveniently manipulated by the attendant or marker at the target butt, and which will clearly indicate to the squad at the firing 20 line, approximately the exact spot where the bullet hit the target.

This object is attained by providing at the firing line of the range, an indicator which on its face may have a facsimile of the target, annunciators numbered to correspond 25 with the value of the hit, annunciators lettered and arranged clock like to indicate the annular position of the hit, and annunciators with characters for indicating the radial location of the hit in the value and at the annular location indicated by the other characters. This indicator is connected by suitable battery circuits with a transmitter that is located at the butt, and which has push 30 buttons, or other forms of circuit closers, that may be arranged in any convenient manner, but are desirably arranged and marked similarly to the annunciators of the indicator, whereby, the attendant at 35 the butt, upon noting the location of a hit, without disturbing the target, closes the proper circuits which cause that location to be instantly indicated to those at the firing line.

40 The drawing shows a diagrammatic representation of a preferred form of an apparatus which embodies this invention.

The indicator 1, is set up in any convenient locality at the firing line, where it can be 45 observed by the person firing and the score-keeper.

The indicator illustrated has on its face a miniature representation of the target. With the target shown, which is the common 50 style of military target, a shot striking the bull's-eye is given the value of 5. A shot in

the inner white ring has a value of 4. A hit in the outer white ring has the value of 3, and one in the white field of the target, outside of the rings, is marked 2, while a miss 55 is, of course, 0.

At the top of the face of the indicator 60 shown are five openings, and in proximity to these openings it is desirable to have printed the word "Value". Back of these 65 openings there may be arranged the numerals 0, 2, 3, 4, and 5, and covering these 70 may be annunciator shutters constructed to be dropped by any common type of annunciator magnets.

75 Arranged annularly about the outer ring of the target shown on the indicator that is illustrated, may be openings through which 80 may be seen the usual lettering of a clock. Annunciator shutters may be arranged to 85 cover these clock figures, and an annunciator magnet of common form may be arranged to operate each of these shutters. At the bottom of the face of the indicator illustrated are three openings which may be lettered "Inner", "Center", "Outer". It is 90 convenient although not essential to have back of these openings the characters +, 0, and -. Shutters may be arranged to cover these characters, and annunciator magnets 95 arranged to drop these shutters.

The annunciator magnets are not shown, for any common form, well known to those skilled in the art, may be used for the purpose of dropping the shutters, and the particular type of annunciator mechanism forms no feature of this invention.

The transmitter 2 is desirably, although not necessarily, provided with a miniature target having the bull's-eye, the inner and 95 outer white rings, and the field space.

Near the upper edge of the face of the transmitter there may be arranged five push buttons, numbered 0, 2, 3, 4, 5.

Arranged clock-wise around the outer 100 ring of the target on the transmitter there may be twelve push buttons marked from I to XII, to correspond with the clock markings on the indicator.

Near the lower edge of the transmitter are 105 three push buttons which may be marked +, 0 and -.

A cable 3, connects the transmitter with the indicator. With the form of apparatus shown this cable consists of twenty wires. 110 These wires are connected so that the 0, 2, 3, 4, and 5 "value" annunciators of the indi-

cator are in circuit with the correspondingly numbered "value" buttons or circuit closers of the transmitter. The clock-wise arranged and lettered annunciators of the indicator 5 are connected with the clock-wise arranged and lettered circuit closers of the transmitter. The +, 0 and — annunciators of the indicator are connected with the +, 0, and — circuit closers of the transmitter. A common return wire 4, communicating with a battery 5, is arranged to connect the several annunciators of the indicator with the several circuit closers of the transmitter, after the usual manner of connecting up such circuits.

While it is preferred to arrange the circuit closers similarly to the arrangement of the indicator annunciators, for the purpose of eliminating chance of error, this arrangement is not essential to the invention, as the circuit closers could be arranged in any other desired manner.

After a shot has been fired, the attendant at the butt usually first presses the transmitter button, either 0, 2, 3, 4, 5, which indicates the value of the shot. He may then press one of the clock-wise arranged buttons to indicate the annular position of the hit. Finally he may press one of the buttons, +, 0, —, which indicates the radial position in the value, of the hit, that is, whether in the value it is nearer the next higher value or the next lower value, or is approximately in the center of the value.

If, when this apparatus is installed at a range, a bullet should strike the target, for example as shown in the drawings, at the point X, the attendant at the butt would 40 press the value button 4 and the value annunciator shutter of the indicator would

drop, showing at the firing line that the marksman had scored 4. The attendant could then press the clock button XII. This would drop the shutter on the indicator which would show that circumferentially the hit was in line with XII. The attendant would then press the plus button of the transmitter, which would operate the plus annunciator of the indicator, showing that the shot was good, that is, it was near 50 the inner edge of the value 4.

By the employment of this simple apparatus, the location of a hit on a target is instantly indicated to the person firing, so that he may regulate his aim for the next 55 shot to overcome any fault in his previous aim.

The invention claimed is:

A rifle range indicator including an indicator bearing a miniature target and provided with value-indicating annunciators, radial position annunciators and diagrammatically arranged annunciators to indicate the annular location, said value-indicating annunciators being disposed along one side of the miniature target and said radial position annunciators being arranged along another side of said miniature target, and a manually operated transmitter bearing a miniature target having push buttons arranged for controlling the value-indicating annunciators and also a radial position annunciator and having push buttons diagrammatically arranged for controlling the annunciators indicating the annular location.

EARL D. CHURCH.
